UNITED STATES PATENT OFFICE.

WILLIAM H. HOLLAR, OF PHILADELPHIA, PENNSYLVANIA.

VAULT.

No. 841,398.

Specification of Letters Patent.

Patented Jan. 15, 1907.

Application filed October 13, 1906. Serial No. 338,697.

To all whom it may concern:

Be it known that I, WILLIAM H. HOLLAR, of Philadelphia, in the State of Pennsylvania, have invented certain new and useful 5 Improvements in Vaults, whereof the following is a specification, reference being had to the accompanying drawings.

My invention relates particularly to means for ventilating during business hours vault- 10 inclosures which are required to be hermetically sealed at other times; and it is an object of my invention to provide means for effecting such ventilation by connection with the ventilating system of the building in which 15 the vault is located without the necessity of providing any opening in the vault other than is required for access to the vault contents.

As hereinafter described, my invention 20 comprises the provision of an auxiliary inclosure exterior to the vault and inclosing an opening ordinarily required for access to the vault—for instance, the emergency-doorway—said auxiliary inclosure being the terminal 25 of a permanent duct connected with the ventilating system of the building, the port between said duct and said auxiliary inclosure being controlled by a valve or register and the arrangement being such that 30 when the emergency-door is opened continuous pneumatic connection may be established therethrough between the interior of the vault and the exterior ventilating system, so that air may be supplied to or withdrawn 35 from the vault in connection with said system without disturbing or modifying the ordinary construction, arrangement, or operation of the vault.

I am aware that other systems have been 40 proposed for effecting the ventilation of vault-inclosures; but, as far as I am aware, they either require openings leading to the vault independently of the ordinary openings controlled by doors provided with locks, 45 or they require the provision of collapsible or removable pipes which extend through and obstruct the openings whereby access is had to the vault and which must be removed when it is desired to close the vault and re- 50 placed when it is desired to ventilate it. Therefore my present improvement is advan- 55 tageous in that the ordinary system of ventilation of the building is not only extended to and made effective with respect to the vault- inclosure whenever the latter is opened for business, but the vault may be closed her-

metically in the usual manner and by the usual means without the necessity of removing or replacing any pneumatic connections.

My invention comprises the various novel 60 features of construction and arrangement hereinafter more definitely specified.

The accompanying drawing is a diagrammatic plan view of the rotunda of a bank-building in which is located a vault-inclosure 65 conveniently embodying my improvement.

In said drawing, 1 is the wall of the rotunda, 2 the outer vestibule thereof, and 3 the corridor leading from the vestibule to the interior of the rotunda through the doorways 70 4 and 5 and to the vault-inclosure 7 through the doorway 8, provided with the outer door 9, vestibule 10, and inner doors 11 and 12.

The rotunda-chambers 14 are provided with booths 15 and 16, the latter having doorways 17, through which access may be had to the auxiliary ventilating-inclosure 20, which extends between the rear wall 21 of the vault 7 and the wall 1 of the rotunda and is provided with the doorways 23, having the 80 doors 24 opening into the respective booths 16. Said inclosure 20 is provided with the partition 26, having the doorway 27 and door 28, so that the inner chamber 29 of said inclosure 20 may be hermetically sealed by closure of 85 the door 28 without preventing access between said booths 16 through the doorways 23 and chamber 30. Said chamber 29 incloses the emergency-doorway 35, which latter is provided with the emergency-door 36, 90 in the rear wall 21 of the vault and is also conveniently provided with the vestibule 38, having the inner doors 39 and 40, covered by the grill 41, having the door 42. Said chamber 29 is provided with the port 45, commun- 95

inating with the duct 46, which extends in communication with the ventilating system of the building, and said port may be provided with any convenient device for opening or closing it, such as a slat-register 47, valve, 100 or slidable door. Although I prefer to extend said duct 46 beneath the inclosure 20 and locate the port 45 in the floor thereof, it is to be understood that connection of said inclosure with the ventilating system of the 105 building may be effected in any convenient manner. For instance, if the ducts of the ventilating system are arranged overhead connection may be made therewith through the ceiling of the inclosure 20.

The arrangement above described may be utilized as follows: At other times than busi-

ness hours the vault-inclosure 7 is hermetically sealed by the outer door 9 and the emergency-door 36. However, at the beginning of business hours the outer door 9 and front 5 vestibule-doors 11 and 12 being opened, the emergency-door 36 and its vestibule-doors 39 and 40 are likewise opened. Thereupon the register 47 in the ventilating-chamber 29 may be opened, thus establishing communication between the ventilating system of the building, comprising the duct 46, and the interior of the vault-inclosure 7, so that air may be withdrawn through the front doorway 8 and the emergency-doorway 15 35, or air may be forced through said doorway in the reverse direction, with the effect of receiving the atmosphere in said inclosure 7, the direction of passage of the air being of course determinable in accordance 20 with whether the ventilating system is of the exhaust or plenum type.

It is also to be understood that I do not desire to limit myself to the provision of but a single port within the inclosure 20, as it 25 may be provided with both an inlet-port and an outlet-port for connection with a ventilating system of the combined exhaust and plenum type. Moreover, it is to be understood that I do not desire to limit myself to 30 the precise details of construction and arrangement above described, as various modifications may be made therein without departing from the scope of the following claims.

35 I claim—

1. The combination with a vault provided with a doorway, of a door arranged to hermetically seal said doorway; an auxiliary inclosure exterior to said doorway; and, a

permanent ventilating-duct terminating in 40 said inclosure, and connected with a ventilating system, substantially as set forth.

2. The combination with a vault provided with a doorway, of a door arranged to hermetically seal said doorway; an auxiliary 45 inclosure exterior to said doorway; a permanent ventilating-duct terminating in said inclosure and connected with a ventilating system; and, means in said auxiliary inclosure arranged to control the port of said duct 50 independently of said door, controlling said doorway in the vault-inclosure, substantially as set forth.

3. The combination with a vault provided with a doorway, of a pneumatic duct permanently located with respect to said vault and terminating in a port exterior thereto; an auxiliary inclosure, exterior to said vault, connecting said port with the doorway of 55 said vault; and, a doorway provided with a 60 door in said auxiliary inclosure, substantially as set forth.

4. The combination with a vault provided with a doorway, of a pneumatic duct permanently located with respect to said vault and 65 terminating in a port exterior thereto; an auxiliary inclosure, exterior to said vault, connecting said port with the doorway of said vault; and, means in said auxiliary inclosure arranged to control said port, independently 70 of said vault, substantially as set forth.

In testimony whereof I have hereunto signed my name, at Philadelphia, Pennsylvania, this 12th day of October, 1906.

WILLIAM H. HOLLAR.
